Primary Examiner — Steven J Czyz(74) *Attorney, Agent, or Firm* — WPAT, PC(57) **CLAIM**

The ornamental design for a moisture-proof pill organizer, as shown and described.

DESCRIPTION

FIG. 1 is a perspective view of a moisture-proof pill organizer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and

FIG. 7 is a bottom view thereof; and,

FIG. 8 is another perspective view thereof.

The broken lines shown in the drawings depict portions of the article that form no part of the claimed design.
